UNITED STATES PATENT OFFICE.

FRANK C. HOBBS, OF MUSKEGON, MICHIGAN, ASSIGNOR TO BRUNSWICK-BALKE-COLLENDER CO., A CORPORATION OF DELAWARE.

DISCHARGEABLE POCKET FOR POCKET-BILLIARD TABLES AND THE LIKE.

1,116,889.

Specification of Letters Patent.

Patented Nov. 10, 1914.

Application filed May 18, 1914. Serial No. 839,355.

To all whom it may concern:

Be it known that I, FRANK C. HOBBS, a citizen of the United States, and a resident of the city of Muskegon, in the county of Muskegon and State of Michigan, have invented certain new and useful Improvements in Dischargeable Pockets for Pocket-Billiard Tables and the like; and I do hereby declare that the following description of my said invention, taken in connection with the accompanying sheet of drawings, forms a full, clear, and exact specification, which will enable others skilled in the art to which it appertains to make and use the same.

This invention relates generally to improvements in dischargeable pockets for pocket billiard tables and the like, and it consists, essentially, in the novel and peculiar combination of parts and details of construction, as hereinafter first fully set forth and described and then pointed out in the claims.

In the drawing already referred to, which serves to illustrate my said invention more fully, Figure 1 is an elevation of a fragment of a pocket billiard table, indicating my dischargeable pocket thereon as a corner pocket. Fig. 2 is a vertical section in line 2—2 of Fig. 1. Fig. 3 is a like section of a fragment of the said pocket showing the lower end thereof in discharging position.

Like parts are indicated by corresponding symbols and characters of reference in all the figures of the drawing.

The essence of my invention resides in the provision of easily actuated and simple and efficient means whereby billiard balls may be removed from the pockets of pocket billiard tables without the necessity of reaching into said pockets, and removing the same by hand, and, to better understand the said invention, reference is now made to the drawings, in which—

A indicates a fragment of a typical pocket billiard table.

B is the billiard cloth; C, the slate bed; D, the slate frame; E, the head block; H, the pocket iron; and I, the pocket proper.

Attention is now drawn to the fact that while the drawings illustrate the pocket as a corner pocket, the same may be applied to the side of the table, to form side pockets,

without change or modification except as to the employment of a suitably shaped pocket iron.

The pocket I is in this instance formed from a flat blank of leather into cylindrical shape, the adjoining and overlapping longitudinal edges of which are riveted or otherwise secured together as at 1. The upper portion of the leather pocket is of equal diameter, and considerably larger than the diameter of a billiard ball, but the lower portion thereof gradually tapers down in diameter on a neatly swept curve until the lower end or outlet is but very little in excess of the diameter of the billiard balls. One side of the lower end is cut away as at 2 to provide a side outlet from said pocket.

Closing the lower end of the pocket I there is a hinged cup J which cup is pivoted to said pocket by pivots 3 at a point forwardly or outwardly of the medial line of the pocket, so that the weight of a billiard ball 4 dropped into said cup, plus the remainder of the spheres in said pocket will tend to maintain said cup in closed position. The outward portion of the wall of cup J is cut away at 5 to coincide with the cut-away portion 2 of the pocket I, the whole forming an essentially elliptical opening K of insufficient size to permit the egress of the billiard balls. Outward or forward motion of said cup is prevented by the up-standing rear wall of said cup contacting with the lower back wall of the pocket I as clearly seen in Fig. 2.

When it is desired to remove the billiard balls from the pocket I the palm of the right hand may be applied to the lip L of the cup J with the fingers underneath said cup and same swung backwardly. As this movement proceeds, the ball 4 contacts with the rear wall of the lower end of the pocket I and is gradually elevated out of the opening K and over the lip L. Meantime the opening K' is becoming larger until finally, when the ball 4 has been sufficiently elevated, the said opening will be large enough to permit the automatic ejection of the ball into the palm of the hand. It will now be observed that as the ball drops into the palm of the hand, the opening K' is closed to succeeding balls, and if the hand be removed from contact with the lip L, the cup will return to its normal

position before another ball can drop through the opening K; thereby preventing the egress of succeeding balls until the discharging operation is repeated. In this manner control of the discharge of the balls is effected, and there is no danger of a plurality of balls issuing from the pocket in rapid succession, overflowing the palm of the hand, dropping to the floor, and rolling into inaccessible places, as is now the case with other discharging pockets.

On the interior of pocket iron H at the lower edge thereof is produced a recess 6 into which the upper end of the pocket I is adapted to fit and wherein it is secured in any suitable manner. In the wall of said pocket, adjacent the slate bed E of the pocket billiard table A, there is produced a cut away portion 7, to permit the ingress of the balls into the pocket.

The walls of the pocket I may be perforated with a plurality of perforations 8 of any preferred design to enhance the appearance thereof for obvious reasons. It is not necessary that the said pocket be made from leather. Any other suitable material may be employed. The same may be drawn from light sheet metal in the well known process of drawing with the interior lined with a thin leather lining to prevent metallic contact of the billiard balls, and the exterior nicely nickelized or silver plated and buffed or polished to a high finish, if desired.

In cases of tables provided with troughs or runners underneath the table leading from each pocket to a common point, where a receptacle for the reception of all the billiard balls is located, the opening K in pocket I and cup J is located on the inner or opposite side of said parts so that said balls may gravitate into such troughs or runners.

While herein I have described the preferred method of practising my invention, I reserve the right to make such changes and alterations as might suggest themselves to one skilled in the art or permitted under the doctrine of equivalents.

It is now to be understood that I do not confine the application of my invention to billiard balls alone. The same may be applied to billiard chalk holders, for instance, or to bowling alleys for the reception of bowling balls, or to marble containers in novelty stores and the like, without departing from the spirit or scope of the invention.

It will be observed that in the act of moving the cup shaped structure J out of the way the balls are slightly elevated so as to insure their egress over the lip L.

Having thus fully described my invention I claim as new and desire to secure to myself by Letters Patent of the United States:

1. In combination, a shell having an opening at the upper and lower ends thereof, a

cup shaped closure pivoted at the said lower end, there being coinciding cutouts in the side walls of said shell and said closure, and means in connection with said shell, whereby when said closure is tilted backwardly, objects introduced into said pocket and closure are elevated and ejected through said cutouts.

2. A dischargeable pocket comprising a cylindrical member having an open lower end and a tiltable cup shaped member closing said end, said cup being pivoted to said cylindrical member forwardly of the medial lines of said cup and member, said cup having means limiting the forward motion thereof, whereby the weight of billiard balls introduced into said member will maintain said cup in closed position.

3. A dischargeable pocket comprising a cylindrical member having an open lower end and a tiltable cup shaped member closing said end, said cup being pivoted to said member forwardly of the medial lines of said cup and member, said cup having means limiting the forward motion thereof, whereby the weight of billiard balls introduced into said member will maintain said cup in closed position, there being coinciding cutouts in the walls of said cup and member of lesser diameter than said billiard balls.

4. In combination, a shell having an opening at the upper and lower ends thereof, a cup shaped closure pivoted at the said lower end forwardly of the medial line of said shell and closure, there being coinciding cutouts in the side walls of said shell and said closure, and means in connection with said shell, whereby when said closure is tilted backwardly, objects introduced into said pocket and closure are elevated and ejected through said cutouts.

5. In combination, a shell having an opening at the upper and lower ends thereof, a cup shaped closure pivoted at the said lower end, and possessed of an axial opening in the bottom thereof adapted for the reception of objects introduced into said shell, said opening being of lesser size than said objects, there being coinciding cutouts in the side walls of said shell and said closure, and means in connection with said shell, whereby when said closure is tilted backwardly, said objects are elevated and ejected through said cutouts.

6. In combination, a shell having an opening at the upper and lower ends thereof, a cup shaped closure pivoted at the said lower end forwardly of the medial line of said shell and closure, and possessed of an axial opening in the bottom thereof adapted for the reception of objects introduced into said shell, said opening being of lesser size than said objects, there being coinciding cutouts in the side walls of said shell and said closure, and means in connection with said shell,

whereby when said closure is tilted backwardly, said objects are elevated and ejected through said cutouts.

7. In combination, a suitable shell having an entrance to the interior thereof, and an independent outlet therefrom, tilttable hand actuated means below said shell adapted for the elevation and ejection through said outlet of objects introduced into said shell.
- 10 8. In combination, a suitable shell having an entrance to the interior thereof, and an independent outlet therefrom, tilttable hand actuated means below said shell, and means on said shell co-acting therewith, adapted for the elevation and ejection through said outlet of objects introduced into said shell.
- 15 9. In combination, a pocket having an entrance thereto and exit therefrom, a cup shaped closure pivoted at the lower end of said pocket forwardly of the medial line of said pocket and said closure, there being coinciding cutouts in the walls thereof at a right angle to the pivotal axis of said closure, and an opening in the bottom of said 20 closure of smaller size than objects intro-

duced into said pocket and closure, whereby, when said closure is tilted backwardly, said objects are elevated and ejected from said closure through said cutouts.

10. In combination, a pocket having an entrance thereto and exit therefrom, a cup shaped closure pivoted at the lower end in said pocket forwardly of the medial line of said pocket and said closure, the back wall of the lower end of said pocket projecting into 30 said closure, there being coinciding cutouts in said pocket and said closure, whereby, when said closure is tilted backwardly, objects introduced into said pocket and closure are elevated and ejected from said closure 35 through said cutouts by contacting with said back wall.

In testimony whereof I have hereunto set my hand in the presence of two subscribing witnesses.

FRANK C. HOBBS.
